VENEERING CONSTRUCTION

Filed Oct. 22, 1930

UNITED STATES PATENT OFFICE

EDWARD J. MASON AND HENRY W. MASON, OF DETROIT, MICHIGAN

VENEERING CONSTRUCTION

Application filed October 22, 1930. Serial No. 490,399.

Our invention relates to a new and useful improvement in a veneer construction adapted for use primarily in veneering existing buildings with brick.

It is an object of the present invention to provide a veneering construction for existing buildings whereby expensive excavating and foundation building may be dispensed with and a suitable, firm support for the layer of veneering provided so as to reduce the cost of veneering to a minimum and provide a construction by which the owners of existing buildings may economically veneer the same.

It is another object of the invention to provide a supporting structure carried by the original foundation of the building which will serve to support the veneering in a durable, substantial and satisfactory manner.

Another object of the invention is the provision of a horizontally positioned supporting member disposed exteriorly of a foundation wall sufficiently outwardly therefrom to support a layer of veneering such as brick and the like and provided with means for attaching firmly to the foundation wall of the building.

Other objects will appear hereinafter.

The invention consists in the combination and arrangement of parts hereinafter described and claimed.

The invention will be best understood by a reference to the accompanying drawings which form a part of this specification and in which,

Fig. 1 is a fragmentary vertical sectional view of a building showing the invention applied.

Fig. 2 is a fragmentary side elevational view of a building showing the invention applied, with a part broken away.

The invention is intended for use particularly on existing buildings and its use affords a means for economically veneering existing buildings such as frame and stucco buildings. With construction methods as now used, it is customary in order to brick veneer an existing building to excavate exteriorly of the foundation to the footing and provide extra width of foundation on the

exterior. This is an expensive operation and entails considerably more expense than would be required to place the veneering on the building at the time of its construction.

In the drawings we have illustrated the invention applied to an existing building having a foundation wall 7 resting on a footing 8 and provided with the basement floor 9, all of which are customarily formed from concrete. A section of the dwelling which is supported by the foundation 7 is illustrated, the siding 10 of which extends downwardly behind the board 11.

Substantially flush with the grade line 12 we secure in horizontal position an angle iron 13 having the vertically extending portion 13 and the horizontally extending portion 14. A bolt 15 having a squared head 15' is projected through the angle iron portion 13 and through the foundation wall 7, suitable washers 16 serving to space the angle iron 13 outwardly a slight distance from the foundation wall. A washer 18 is positioned on the bolt 15 which is provided with the nut 17. Balsam wool or other suitable insulating material 19 is positioned in the space 22 which separates the layers 21 of brick veneering from the outer surface of the foundation wall 7 and the outer surface of the siding 10. Wall ties 22' are secured to the foundation wall and to the siding at spaced intervals.

A mass of concrete 23 is used to encase the supporting angle iron and the heads 15' of the bolts project therethrough so that corrosion is reduced to a minimum. This mass of concrete is supported on a washer 25 which depends from the angle iron portion 14 by means of the bolt 24.

With this type of structure, the veneering may be cheaply and easily applied to an existing building and at the same time sufficient support is given to the layer of veneering to retain it in position. It has been found in practice that by reducing the depth of the brick 21 from the depth of a standard size brick, the purposes of the veneering are obtained and the weight is considerably reduced. It will be noted that the portion 14 of the angle iron serves as the supporting member or plate to support the layer of veneering and

that the portion 13 serves as a reinforcement of this plate and co-operating with the bolts forms the attaching means for securing the supporting member 14 in position.

While we have illustrated and described the preferred form of construction of our invention, we do not wish to limit ourselves to the precise details of structure shown but desire to avail ourselves of such variations and modifications as may come within the scope of the appended claims.

Having thus described our invention, what we claim is:

1. A veneering construction adapted for use on structures having a foundation wall projecting upwardly from the grade line, comprising: a horizontally disposed supporting plate secured to and projecting outwardly from the outer surface of said foundation wall; a layer of veneering supported on and projecting upwardly from said supporting plate; and a concrete mass for encasing said plate and its securing means.
2. A veneering construction adapted for use on structures having a foundation wall projecting upwardly from the grade line, comprising: a horizontally disposed supporting plate secured to and projecting outwardly from the outer surface of said foundation wall; a layer of veneering supported on and projecting upwardly from said supporting plate; a concrete mass for encasing said plate and its securing means; and means on said plate for supporting said concrete mass.
3. A veneering construction adapted for use on structures having a foundation wall, comprising: a horizontally disposed supporting member secured to and projecting outwardly from the outer surface of the said foundation wall; a layer of veneering supported on and projecting upwardly from said supporting member; and means for encasing said supporting member.

In testimony whereof we have signed the foregoing specification.

EDWARD J. MASON.
HENRY W. MASON.
